UNITED STATES PATENT OFFICE.

MORRIS A. BORDMAN, OF PHILADELPHIA, PENNSYLVANIA.

SADIRON.

Application filed April 10, 1924. Serial No. 705,516.

To all whom it may concern:

Be it known that I, MORRIS A. BORDMAN, a citizen of the United States, residing in Philadelphia, Pennsylvania, have invented 5 certain Improvements in Sadirons, of which the following is a specification.

One object of my invention is to provide an improved construction for use in connection with sad irons of the type known as 10 "self heating" irons where combustible fuel is placed in a hollow body portion of the iron; the invention including improved and novel actuating means which can be easily and quickly moved to vary the 15 amount of draft of air through the iron.

Another object is to so construct my invention that when applied to an iron, the latter can be manipulated and kept at a desired operating temperature and the draft 20 regulation can be conveniently and accurately effected without waste of time.

These objects and other advantageous ends which will be set forth hereinafter, I attain in the following manner, reference being had to the accompanying drawing, in 25 which—

Figure 1 is a side elevation of a sad iron having my invention thereon,

Figure 2 is a sectional top plan view taken 30 on the line 2—2 of Figure 1,

Figure 3 is a sectional elevation taken on the line 3—3 of Figure 2, and

Figures 4 and 5 are top plan views of certain of the elements of my invention.

Referring to the drawing, 10 represents the hollow base or body portion of the iron for containing the combustible fuel. This base is open at its top but is normally provided with a flat top or cover plate 11 which 35 has a tongue 12 adapted to enter a notch 13 in the front part of the base 10. A bolt or pin 14 extends through a hole in a lug 15, said lug projects upwardly from the rear of the base 10, the pin extending over 40 the cover plate 11 and under the bottom 16^a of the handle 16. In the arrangement as illustrated, parallel lugs 17 on the cover plate form a groove or channel in which the pin 14 can slide, and the tongue 12 and 45 pin 14 hold the cover plate to the base. In the drawing the handle 16 is shown riveted to the cover plate but can be secured thereto in any other suitable manner.

The front flat portion 18 of the cover 55 plate 11 has a number of draft air holes 19, and the rear flat portion 20 of the cover

plate 11 has a number of draft air holes 21. A shutter 22 is slidably mounted below the cover plate 11 and includes a shutter plate 23 and a projection or stem 24, said stem 60 having a row of teeth 25 which constitute a rack adapted to mesh with a toothed gear wheel 26. The gear wheel 26 is secured to an upright shaft or spindle 27 which rotatably fits within a hole in the cover plate 11 and extends upwardly through a hole in the bottom 16^a of the handle 16. A knob or finger piece 28 is secured to the top of the spindle 27 at a position spaced below the hand grip 29 of the handle 16. A second shutter 30 has a shutter plate 31 and a projection or stem 32 provided with a row of teeth 33 adapted to mesh with the gear wheel 26 at a position diametrically opposite the point of intermesh of the gear wheel 26 70 with the teeth 25 of the shutter 22.

The shutter 30 is positioned below the cover plate 11 in the plane of the shutter 22. A flat plate 34 is positioned below the shutters 22 and 30 and is secured to the top plate 11 preferably by rivets 35 which are arranged in rows as shown in Figure 2, and serve as guiding means for the stems 24 and 32 of the shutters 22 and 30. The rivets 35 also serve to keep the respective rows of teeth 25 and 33 in mesh with the gear wheel 26. The shutter plate 23, when in the position shown in Figures 2 and 3, serves to close the holes 19 and likewise the shutter plate 31, as shown in Figures 2 and 90 3, serves to close the air holes 21. By turning the finger piece 28 clockwise, the stems 24 and 32 of the shutters 22 and 30 will be slid lengthwise with a parallel motion and the shutter plates 23 and 31 will be 95 moved toward each other and open the holes 19 and 21. If desired all of these holes can be opened or parts of the holes may be opened thus allowing more or less draft for the fuel within the iron. 100

Any suitable lower draft holes or apertures can be formed in the base 10 and I have illustrated apertures 36 and movable cover plates 37. I preferably provide a layer of insulating material as shown at 38 105 in Figure 3, said layer of insulating material being positioned between the plate 34 and a bottom plate 39. The plate 39 can be supported by the rivets 35 and I preferably provide spacing portions 40 on the rivets 35 so as to keep sufficient space 110 between the top plate 11 and the plate 34

to allow the free sliding movement of the shutters. If desired any suitable hoods can be used on the interior of the base for preventing the fuel from working out of the 5 apertures 36, and in the present instance I have shown in Figure 3 a hood 41 for said latter purpose.

Having thus described my invention what I claim as new and desire to secure by Letters Patent is:

1. An iron of the character described provided with a draft passage in one part of the iron and a draft passage in another part of the iron; independent shutter portions for said passages; and common means operative to effect movement of said shutter portions to open or close said passages or to vary the amount of opening of said passages.
2. An iron of the character described provided with a draft passage in one part and a draft passage in another part; shutters having rows of teeth; and common operating means for said shutters including a gear wheel meshing with the teeth of each shutter.
3. An iron of the character described provided with a draft passage in one part and a draft passage in another part; shutters

having rows of teeth; and common operating means for said shutters including a gear wheel meshing with the teeth of each shutter, said teeth being opposed to each other with the gear wheel positioned between said rows of teeth.

4. An iron of the character described provided with an air passage in its forward part and an air passage in its rear part; draft controlling shutters for said passages respectively having rearwardly and forwardly extending stems; guiding means for said stems; and common means for sliding said stems forwardly and rearwardly to actuate said shutters relatively to the draft passages.

5. An iron of the character described provided with a cover having flat portions each having draft holes therein; a shutter for controlling the holes of each portion and slidably carried by said cover; and common actuating means for said shutters.

In testimony whereof, I have signed my name to this specification, in the presence of two subscribing witnesses.

MORRIS A. BORDMAN.
